BOX FORMING MACHINE

Joseph P. Mancuso, Jamesburg, and Robert R. Maffett, Westfield, N. J., assignors to Robert E. Bauer, Wyndmoor, Pa.

Application June 8, 1954, Serial No. 435,154

10 Claims. (Cl. 93—51)

The present invention relates to new and useful improvements in packaging machines and more particularly to new and useful improvements in machines for forming a paper or cardboard box, inserting an article in the box and then sealing the box with cellophane or like material.

A primary object of the present invention is to provide a novel packaging machine wherein a continuous supply of box blanks may be fed to the machine and formed into boxes which receive the articles to be packaged and are then automatically sealed by the machine.

Another object of the present invention is to provide a novel packaging machine wherein a box blank may be rapidly and automatically formed into a finished box.

A further object of the present invention is to provide a novel packaging machine wherein an article, such as a pie plate is automatically inserted into a finished box positioned beneath a supply of the articles carried by and automatically fed one at a time by the packaging machine.

A further object of the present invention is to provide a novel packaging machine wherein sheets of cellophane or like material are automatically severed from a continuous roll and secured across the open upper end of a finished box being conveyed longitudinally of the machine.

A still further object of the present invention is to provide a novel packaging machine having the features and characteristics set forth which is of relatively simplified construction, operates automatically with a minimum amount of attention by the operator, and is highly efficient and effective in operation and use.

These and other objects of the present invention and the various features and details of the operation and construction thereof are hereinafter more fully set forth and described with reference with the accompanying drawings, in which:

Fig. 1 is a side elevational view of the box forming and packaging machine of the present invention;

Fig. 2 is a perspective view of a box blank which is folded and assembled by the machine of the present invention;

Fig. 3 is a perspective view of a box blank in the assembled position with the pie plate and pie positioned therein;

Fig. 4 is a perspective view of the completed package formed in accordance with the present invention;

Fig. 33 is a plan view of the apparatus shown in Fig. 32;

Fig. 34 is a perspective view of one side of the pie plate guide means;

Fig. 35 is an enlarged transverse sectional view taken

on line 35—35, Fig. 32 showing a pie plate feeding mechanism at the start of a feeding operation;

Fig. 36 is an enlarged fragmentary sectional view of the feeding mechanism illustrated in Fig. 32;

Fig. 37 is a sectional plan view taken on line 37—37, 5 Fig. 36 showing a pie plate being dropped into an assembled box;

Fig. 38 is a fragmentary sectional view illustrating the means for dropping one pie plate at a time;

Fig. 39 is a perspective view of the support and feed mechanism for the pie plates; 10

Fig. 40 is a side elevational view of the cellophane feeding and applying mechanism of the present invention;

Fig. 41 is a sectional plan view of the cellophane applying apparatus taken on line 41—41, Fig. 40; 15

Fig. 42 is a transverse sectional view taken on line 42—42, Fig. 40 illustrating the cellophane feeding and cutting mechanism;

Fig. 43 is a transverse sectional view of the cellophane feeding and applying apparatus taken on line 43—43, 20 Fig. 41;

Fig. 44 is an enlarged longitudinal sectional view of the cellophane feeding and applying apparatus taken on line 44—44, Fig. 43;

Fig. 45 is an enlarged fragmentary sectional view illustrating the means for guiding the cellophane;

Fig. 46 is a fragmentary side elevational view illustrating the brush mechanism in position for forcing the edges of the cellophane against the glued edges of the box;

Fig. 47 is a fragmentary transverse sectional view taken on line 47—47, Fig. 44 illustrating the means for maintaining the cellophane in position on the feed table.

Fig. 48 is an inverted plan view partially in section taken on line 48—48, Fig. 1 illustrating the drive mechanism for the cellophane feeding and applying apparatus of the present invention;

Fig. 49 is a sectional view taken on line 49—49, Fig. 48 illustrating the intermittent feed of the present invention;

Fig. 50 is a sectional view similar to Fig. 49 with the drive mechanism in an advanced position.

Fig. 51 is an elevational view of a modified form of ram assembly and die for folding the box;

Fig. 52 is a side elevational view partially in section of the ram assembly and die illustrated in Fig. 51;

Fig. 53 is a perspective view of the pusher member operable to open the locking slits in the folded box prior to insertion of the locking tabs;

Fig. 54 is an enlarged fragmentary sectional view of a portion of the die with the folded box fully inserted into the die;

Fig. 55 is a sectional view taken on line 55—55, Fig. 54 illustrating the pusher member opening the locking slits prior to insertion of the locking tabs;

Fig. 56 is a fragmentary sectional view taken on line 56—56, Fig. 54 illustrating the latch member carried by the pedestals for maintaining the box in position on the pedestals;

Fig. 57 is a fragmentary sectional view similar to Fig. 55 with the pedestals raised after the locking slits have been opened illustrating the means for maintaining the locking slits in their open position; and

Fig. 58 is a plan view of one side of the box taken on line 58—58, Fig. 54 illustrating the locking slits in their open position.

Referring more specifically to the drawings and particularly Fig. 1 thereof, the packaging machine of the present invention consists of four general sections designated generally as A, B, C and D. At section A box blanks are fed from a stack of blanks one at a time to box forming mechanism wherein the blanks are folded to their finished shape. A plurality of empty pie plates are supported in a stack at section B of the machine and are deposited one at a time into finished boxes being conveyed longitudinally of the packaging machine from section A. At section C pies are manually inserted into the pie plates which

are positioned in the boxes; and the pies, pie plates and boxes are then conveyed to section D of the machine wherein a cellophane strip is positioned over the open upper end of each filled box and secured to the box to complete the packaging operation.

This packaging machine is operable to receive a box blank 51 formed, for example, as shown in Fig. 2, and fold the box blank 51 into a box 52, as shown in Fig. 3. A pie plate 53 is then inserted into the box 52 by the packaging machine and a pie 54 is manually placed into the pie plate 53 in the box 52 while the box is being moved longitudinally of the machine. After these operations are completed, a strip of cellophane 55 is automatically positioned and glued across the open upper face of the filled box to form the finished product shown in Fig. 4.

The box blank 51 comprises a central base portion 56 having a pair of side wall forming flaps 57, 57 and a pair of end wall forming flaps 58, 58 integrally secured thereto along fold lines 57a and 58a, respectively. Each end wall forming flap 58 has a pair of generally triangular flaps 59, 59 foldably connected to the outer upper edge thereof adapted to extend across the corners of the open upper end of the finished box. The triangular flaps 59, in turn, have locking tabs 61 secured to the outer side edge thereof which outwardly overlie the side wall forming flaps 57 and are locked in position in locking slits 62 in the ends of the side wall forming flaps 57 to maintain the box in its formed position. While the packaging machine of the present invention is illustrated and described in conjunction with the forming and folding of the blank 51, it is apparent that the packaging machine may be readily adapted to fold other box blanks of the same general class as the blank 51.

The entire packaging machine is driven by an electric motor 63 which causes rotation of a pair of shafts 64 and 65 extending outwardly from opposite sides of a gear reducer 66. The shafts 64 and 65, as more fully described hereinafter, operate the mechanism for feeding and forming the box blanks, conveying the formed boxes longitudinally of the machine, inserting a pie plate into the box and securing a sheet of cellophane over the open upper surface of the box.

In accordance with the present invention, a stack of box blanks 51 is supported at the feed end of the packaging machine and the box blanks are automatically formed into boxes one at a time. The boxes are then conveyed longitudinally of the machine toward the discharge end thereof. Figs. 1 and 5 to 14, inclusive (sheets 50 1 to 6 of the drawings), disclose the box blank feeding and forming mechanism of the packaging machine of the present invention. As illustrated in Fig. 5, a stack of the box blanks is positioned between a plurality of guide posts 67 and a weighted member 68 is placed on top of the stack of box blanks to force the same downwardly in the machine.

Positioned laterally of the machine from the stack of box blanks and carried by a ram shaft 71, for example as illustrated in Figs. 8 and 9 of the drawings, is a ram assembly 72 which is mounted for reciprocal movement between upper and lower limit positions. The ram assembly 72 is carried by the lower end of a stub shaft 73 projecting downwardly from a transverse ram arm 74 secured to the upper end of the ram shaft 71. A post 75 extending upwardly from the frame of the packaging machine and containing a pair of slide bearings at the upper and lower ends thereof guides the vertical movement of the ram shaft 71. Means is provided at 71a to maintain the assembly 72 in axial alignment.

Reciprocating movement of the ram assembly 72 is caused by the drive shaft 64 which, through a pair of bevel gears 76, causes rotary movement of a cam shaft 77 extending transversely of the packaging machine. A ram cam 78 is fixedly secured to one end of the shaft 77

and engages a cam follower 81 pivotally carried by the lower end of the ram shaft 71. The ram cam 78 is formed for example as illustrated in Fig. 10 of the drawings and has alternate high and low portions thereon, as illustrated, to cause vertical reciprocating movement of the ram assembly 72.

The ram assembly 72 has a generally rectangular configuration in the horizontal plane corresponding to the shape of the central base portion 56 of the box blank 51. The lower surface of the ram assembly is adapted to engage the central base portion 56 of the box blank during downward movement of the ram assembly and cause the side and end walls 57 and 58, respectively, of the box blank to be folded upwardly along the fold lines 57a and 58a, respectively, to a vertical position.

According to the present invention means are provided to transpose a box blank 51 from the lowermost position in the stack of box blanks to a position wherein the central base portion of the box blank is in alignment with the lower surface of the ram assembly 72. In this position the lower surface of the ram assembly will engage the central base portion of the box blank when traveling to its lower limit position. To accomplish this a box blank shuttle 82 formed for example as illustrated in Fig. 6, is slidably mounted in tracks 83, 83, as shown in Fig. 5, carried by an upwardly projecting frame portion of the packaging machine at the base of the stack of box blanks. The box blank shuttle is mounted for reciprocating movement transversely of the packaging machine between predetermined forward and rearward limit positions and during movement to the forward limit position thereof the box blank shuttle 82 operates to transfer the bottom blank of the stack of box blanks to the aforementioned position in alignment with the ram assembly 72.

Reciprocating movement of the box blank shuttle is effected by means of a shuttle cam 85 formed, for example, as illustrated in Figs. 5 and 9 of the drawings, and secured to the end of the shaft 77 opposite the ram cam 78. A cam follower 86 secured to the lower end of a lever 87 pivoted at its mid-point, as indicated at 88 in Fig. 9, engages the forward surface 91 of the shuttle cam 85 whereby rotation of the shuttle cam 85 effects oscillatory motion of the lever 87 about its pivot 88. A tension spring 92 secured between the frame of the machine and the lower end of lever 87 maintains the cam 85 and follower 86 in operative contact. The upper end of the arm 87 is interconnected with a downwardly projecting lug 93 secured to the lower surface of the box blank shuttle 82 by means of a conventional adjustable coupling 94. By this construction rotation of the shaft 77 effects reciprocation of the box blank shuttle 82 between its opposite limit positions.

With reference to Figs. 6 and 9, the box blank shuttle 82 consists of a flat plate 95 having forwardly extending arm portions 96, 96 at the opposite sides thereof. A supporting plate 97 is secured to the rear portion of the box blank shuttle and is of a thickness substantially equal to the thickness of a single box blank 51. The forward end of the supporting plate 97 is beveled downwardly as indicated at 98 and terminates in a pusher edge 101 which is of slightly less height than the thickness of a box blank. In the rearward limit position of the box blank shuttle 82 the pusher edge 101 is positioned adjacent the edge of the bottom box blank of the stack of box blanks, and the box blanks are supported by the two arm portions 96, 96 of the shuttle 82 while the central portion of the box blank is supported by an adjustable support 100, as shown in Figs. 8 and 9. During movement of the shuttle to its forward limit position the pusher edge 101 engages the side of the box blank and forces the bottom box blank of the stack forwardly along with the shuttle. A trough 102 extends transversely of the

box blank shuttle immediately in front of the pusher edge 101 to collect any abraded fuzz produced by sliding of the box blank shuttle relative to the stack of box blanks. When the box blank shuttle 82 reaches its forward limit position a box blank is supported by the forwardly extending arm portions of the shuttle in a position wherein the base portion 56 of the box blank is in registry with the lower surface of the ram assembly 72.

While the box blank shuttle is being moved forwardly by the shuttle cam 85 the ram cam 78 is also rotated and causes the ram assembly 72 to move downwardly. After the box blank shuttle has reached its forward limit position thereby properly positioning the box blank beneath the ram assembly 72 the ram assembly engages the central portion 56 of the box blank and continues movement toward its lower limit position while the box blank shuttle remains in its forward limit position.

In accordance with the present invention, the initial portion of the downward travel of the ram assembly 72 after engaging the box blank causes the side walls 57 and end walls 58 of the box blank to be folded upwardly along their respective fold lines 57a, 58a. To accomplish this, the box blank is positioned on the box blank shuttle with the end walls 58, 58 thereof overlying the shuttle arms 96, 96 and the inner edges of the shuttle arms 96, 96 have beveled upper portions 104, 104 and vertical lower portions 105, 105 as illustrated in Figs. 6 and 10. In a similar manner the edge of the box blank shuttle interconnecting the rear ends and shuttle arms is beveled as indicated at 106 at the upper end thereof and has a vertical portion 107 at the lower edge thereof. In addition, a forming member 108 is secured to the frame of the packaging machine in a position intermediate the forward ends of the shuttle arms 96, 96, for example as illustrated in Figs. 8 and 9, and has a beveled portion 111 and vertical portion 112 on the inner edge thereof corresponding to the beveled and vertical portions of the box blank shuttle. Downward movement of the ram assembly 72 after engagement with the box blank forces the end walls 58, 58 of the box blank into engagement with the beveled surfaces of the shuttle arms 96, 96 and forces the side walls 57, 57 of the box blank into engagement with the beveled portion 106 of the box blank shuttle and the beveled portion 111 of the forming member 108. This causes the end walls and side walls of the box blank to be folded upwardly along their fold lines. Continued downward movement of the ram assembly forces the side walls and end walls of the box blank into engagement with the vertical portions of the shuttle, shuttle arms and forming member thereby folding the side and end walls of the box blank upwardly to the vertical position.

Immediately beneath the ram assembly 72 and in axial alignment therewith is a die opening 113 formed by the forming member 108, side wall members 114, 114 and an end wall member 115. This die opening 113 corresponds in shape to the external configuration of the box blank with the side and end walls folded upwardly and is adapted to receive the box blank 51 and ram assembly 72. As the ram assembly enters the die opening 113, the shuttle cam 85 causes the box blank shuttle to move to its rearward limit position and the box blank is maintained in the desired shape solely by the external walls of the die opening 113 and the ram assembly 72. In this position of the box blank with the ram assembly partially inserted into the die opening and the end and side walls of the box blank in the vertical position the locking tabs 61 are in alignment with the end walls and extend outwardly beyond the walls of the die opening 113.

While the box blank is in the die opening 113 the triangular flaps 59 are folded downwardly over the corners of the open upper end of the box and the locking tabs 61 are inserted into the locking slits 62 in the side walls of the box to maintain the box in the formed position. The

finished box is then removed from the die opening 113 and a new box blank is inserted into the die opening.

Before the locking tabs 61 may be inserted into the locking slits 62, they must be folded inwardly to a position overlying the side walls of the box. This is accomplished by providing forming cam surfaces 117 at the corners of the die opening 113, for example as illustrated in Figs. 21 and 22, which engage the locking tabs 61 of the box blank 51 and fold the locking tabs inwardly to a position above the side wall 57 of the box blank. The cam surfaces 117 are generally concave in the horizontal plane and converge inwardly and downwardly relative to the side walls of the die opening so that during downward movement of the ram assembly 72 the locking tabs of the box blank are brought into engagement with the cam surfaces 117 and then wiped inwardly to a position in alignment with the side walls. By this construction when the ram assembly 72 reaches a predetermined downward position during its path of travel to its lower limit position the box blank 51 assumes the shape shown in Fig. 25.

Positioned below the die opening 113 at opposite sides thereof as shown in Fig. 9 is a pair of pedestals 118, 118 which are mounted for vertical movement between upper and lower limit positions. The pedestals are mounted for vertical sliding movement in bushings 119, 119 which are carried by the frame of the packaging machine. A pair of coil springs 122, 122 bearing against the frame of the packaging machine and reacting on a cross member 123 which interconnects a pair of stub shafts 124, 124 mounting the pedestals normally urge the pedestals to their lower limit position. The pedestals 118, 118 are caused to move between their upper and lower limit positions by means of a pedestal cam 125 carried by the cam shaft 77 and engaging a cam follower 126 which is carried by a downwardly extending arm 127 formed integrally with the cross member 123. During rotation of the cam shaft 77 the pedestal cam 125 engages the cam follower 126 and forces the pedestals upwardly. Further rotation of the cam shaft 77 and pedestal cam 125 causes the springs 122, 122 to force the pedestals 118, 118, toward their downward limit position.

As illustrated in Fig. 10, the pedestal cam 125 is designed to cause movement of the pedestals toward their upper limit position during the latter portion of downward movement of the ram assembly 72. Accordingly, before the ram assembly reaches its lower limit position the pedestal cam 125 starts moving the pedestals toward their upper limit position. The pedestals 118, 118 engage the lower surface of the box blank being forced downwardly by the ram assembly 72 as the ram assembly reaches its lower limit position and the pedestals travel upwardly for a short distance with the ram assembly. This amount of travel is approximately $\frac{1}{16}$ " and after the pedestals have traveled this short distance with the ram assembly the pedestals reach their upper limit position and are stopped. The ram assembly continues moving upwardly until it has reached its upper limit position. As illustrated in Figs. 9, 12 and 27 a pair of hook members 131, 131 are pivotally secured to the outer edge of each pedestal 118, for example as indicated at 132, and have inwardly extending hook portions at the upper end thereof which engage over the upper end of the side wall portions of the box blank. These hook members prevent the box blank from moving upwardly during upward travel of the ram assembly and cause the box blank to be positioned in the proper position relative to the packaging machine for further forming.

According to the present invention after the ram and pedestal engage opposite sides of the base of the box blank the slits 62 are opened to permit the locking tabs 61 to be inserted therein. To this end four slit openers 133 are pivotally mounted to the ram adjacent the lower surface thereof, for example as illustrated at 134 in Figs. 9 and 13, and has a downwardly projecting tab 135 at its

75 rearward edge which, in the normal position of the slit opener, projects down beyond the lower surface of the ram assembly. A tension spring 136 interconnects slit openers at opposite sides of the ram assembly and maintains the slit openers 133 in the position shown in Fig. 9 with the outer side edge thereof in alignment with the side edge of the ram assembly 72. When the pedestals engage the lower surface of the box blank being forced downwardly by the ram assembly the tab portions 135 of the 10 slit opener 133 are forced upwardly pivoting the slit opener about its pivot point 134 and causing the forward edge of the slit opener to engage the side of the box blank immediately below the slit 62. This breaks the lower portion of the side edge of the box away from the upper portion thereof thus opening the slit 62 to receive the 15 locking tabs 61.

After the pedestals have reached their upper limit 20 position with the hook members 131 in engagement with the upper portion of the side edges of the box, the triangular flaps of the box blank are folded downwardly and the locking tabs 61 are inserted into the slit openings 62. The slit openings must be maintained in their 25 open position before the locking tabs are forced downwardly to insure proper entry of the locking tabs into the slit opening. This is accomplished by a plurality of kicker members 138 pivotally mounted at their mid-point outwardly adjacent the side walls of the die opening 113. One kicker member is provided for each slit opening in the box blank and the upper end portion of each kicker member is positioned to engage the side wall of the box blank immediately above the slit openings, for example as shown in Fig. 29. Each kicker member is actuated to its inwardly projected position by means of an actuating arm 141 having an adjustable 30 stop 142 thereon which engages the rearward surface of the kicker member 138. An actuating arm 141 is provided at each side of the die opening and each arm carries a pair of adjustable stops 142, 142 so that all four kicker members are actuated by the two actuating arms. 35 Coil springs secured between one end of the kickers 138 and associated arms 141 serve to bias the kickers toward their respective stops 142. The actuating arms 141, 141 are mounted on shafts 143, 143 for relative vertical movement with respect to the packaging machine and coil springs 144, 144 normally urge the shafts 143 mounting the actuating arms toward their downward limit position. Vertical movement of the shafts 143, 143 is effected by means of a pair of kicker cams 145, 145 which engage cam followers 146, 146 secured to the 40 lower ends of the shafts 143, 143. The kicker cams are mounted on the cam shaft 77 and are so positioned on the cam shaft that the kicker arms will be caused to move to their inner position immediately after the pedestal has reached its upper limit position with the box 45 in the proper position for insertion of the locking tabs in the locking slits.

After the kickers are in their inner position opening the slits in the side walls of the box, the triangular portion of the box blank 59 and the locking tabs 61 are folded downwardly to insert the locking tabs in the slits. 50 This is accomplished by means of a knife assembly 147 formed, for example as illustrated in Fig. 17 of the drawings. The knife assembly 147 comprises a shaft 148 mounted in bearings in the side walls of the die opening 113. A plate 149 is secured to the shaft and has a pair of side lips 151, 151 extending forwardly therefrom. One knife assembly 147 is mounted at each side of the die opening and the triangular flap portions 55 59 of the box blank lie against the inner surface of the plate 149 with the edges of the locking tabs 61 of the box blank projecting outwardly therefrom adjacent the inner surfaces of the side lip portions 151, 151 of the plate 149. A pair of arcuate knives 152, 152 project outwardly from the forward surface of the side lip portions 151 and are formed with the center of the shaft

148 as the center of the arcuate curve of the knives 152, 152. The inner surface of the plate 149 lies in a plane containing the longitudinal axis of the shaft and in addition, the boxes are so positioned by the pedestals 118, 118 relative to the knife assemblies that the fold line on the box blank about which the triangular flap portion is to be folded lies on the longitudinal axis of the shaft 148. By this construction rotation of the shaft 148 and plate 149 folds the triangular flap portions 59 of the box blank downwardly over the corners of the open upper surface of the box, for example as illustrated in Fig. 29. The arcuate knives 152, 152 of the knife assembly outwardly overlie the locking tabs of the box blank with the forward edges of the knives preceding the forward ends of the locking tabs and turned inward, as illustrated in Fig. 28, so that the knives are first inserted into the slit openings on the side wall of the box blank and the locking tabs follow the knives into these openings.

During rotation of the shafts 148 carrying the knife assembly 147 to its inner position wherein the locking tabs are inserted into the slits the kickers are retracted by the kicker cams 145, 145 to permit free insertion of the locking tabs. A hook 153 is positioned on the knife assembly at each side of the plate 149 and is spring biased to a forward position overlying the upper edge of the triangular flap portions of the box so that the box is held firmly with respect to the rotative axis of the plate 149. This insures proper folding of the triangular flap portions of the box blank along their fold lines.

After the locking flaps are inserted into the slits the kickers are again actuated to their forward position to force the upper portion of the side walls of the box inwardly relative to the locking flaps and cause the side walls of the box to engage flat surfaces on the locking flaps and thereby prevent the locking flaps from being removed from the slit openings. During this position of the kickers the knife assemblies are rotated in their opposite direction to remove the knives from the slit openings.

The operation of the knives is timed in relation to the position and operation of the pedestal so that the knives will insert the flaps into the locking slits of the box when the pedestal is in its upper limit position and the knives will be retracted from the slit openings during downward movement of the pedestals. Operation of the knives is effected by means of a knife cam 156 carried by the cam shaft 77 and engaging a cam follower 157 carried by a shaft 158 mounted for vertical movement relative to the packaging machine. A coil spring 159 normally urges the shaft 158 to its lower limit position while the cam and cam follower forces the shaft to its upper limit position. With reference to Fig. 10, an arm 158a projecting outwardly beyond opposite sides of the shaft 158 and carrying springs 160, 160 connected to lugs 148a, 148a extending inwardly from the shaft 148 of the knife assembly 147 causes rotary movement of the knife assembly to position the knives into the box blank slit openings when the shaft 158 is pulled downwardly. Adjustable stops 160a, 160a secured to the arm 158a engage the lower surface of the members 148a, 148a and force the same upwardly thereby retracting the knives when the shaft 158 is elevated by means of the knife cam 156.

Simultaneously with retraction of the knives the pedestal cam 125 causes the pedestals to move to their lower limit position. When the pedestals reach their lower limit position inwardly extending leg portions of the pedestal hook members 131 engage adjustable stops 161 secured to the frame of the packaging machine. Engagement of the inwardly extending leg portions of the hook members 131 by the adjustable stops 161 causes the hook members 131 to pivot about their pivot points 132 to a position out of engagement with the upper surfaces of the side walls of the box. The box is now resting freely on the

pedestals 118, 118 and may be easily removed therefrom. A conveyor 162 having upwardly extending pins 163 thereon passes between the pedestals 118, 118 and in the lower limit position of the pedestals the pins project upwardly beyond the upper surface of the pedestals thereby engaging the box supported on the pedestals and remove the box from the pedestals. This conveyor 162 and pins 163 convey the formed box to further treating apparatus as more fully described hereinafter.

10 Figs. 18 to 31, inclusive (sheets 7 and 8 of the drawings), illustrate the various steps in the formation of a box by the packaging machine of the present invention. At the start of one cycle of operation of the machine the shuttle cam 85 is causing the shuttle to be moved to its projected position in order to properly position the box blank beneath the ram assembly. The ram assembly is at rest in its upper limit position while the pedestals 118 are being moved downwardly by the pedestal cam 125. The knives and the kickers are at rest in their retracted position. After the pedestals reach their lower limit position the fingers 131 are disengaged from the sides of the formed box carried thereby and the conveyor advances one step, as more fully described hereinafter, to remove the formed box from the pedestals. The elevator remains in this lower limit position while the ram assembly 72 starts downwardly.

Before the ram assembly has reached a position level with the shuttle, the shuttle has reached its inner limit position and remains in this position while the box blank

30 is engaged by the ram assembly following which the side and end walls are bent upwardly during continued downward movement of the ram assembly by folding the side and end wall flaps of the box blank over the forming edges of the box blank shuttle 82 and the forming member 113. When the ram assembly 72 reaches a position wherein the base of the box is inserted into the die opening 114, the box blank shuttle is moved to its rearward limit position and the ram assembly continues downward travel to meet the upwardly moving pedestals 118, 118.

40 Upon engagement of the base of the box blank with the pedestals 118, 118, the hooks 131 carried by the pedestals engage the upper ends of the side walls of the box to secure the box in position on the pedestals. The ram assembly is then retracted to its upper limit position and remains in this position until the start of the next cycle of operation.

The pedestals now supporting the partially folded box blank continue movement to their upper limit position to properly position the partially folded blank within the forming cavity 113 and remain in this upper limit position while the locking tabs are being inserted into the slits in the side walls of the box. To insert the locking tabs into the locking slits of the box side walls the kicker members 138 are first actuated to their inner limit position to open the slits and the kicker members are retracted while the knife assemblies 147 are rotated downwardly thereby inserting the knife blades 152 and the locking tabs 61 into the slits 62. The knife assemblies are then rotated in the opposite direction to withdraw the knives from the locking slits and the kickers are again actuated to their inner limit position to lock the locking tabs in the slits. While the knives are being retracted the pedestal cam 125 lowers the pedestals 118, 118 downwardly to their lower limit position wherein the pins 163 extending upwardly from the endless conveyor 162 engage the finished box blank and remove the same from the pedestal. This completes one cycle of operation of the packaging machine of the present invention.

After the box blank is folded to the position shown in Fig. 31 to form a completed box it is conveyed to section B of the machine wherein an empty pie plate 53 is automatically inserted into the formed box through the open upper end thereof. With reference to Figs. 32 and 33, a stack of empty paper pie plates 53 is positioned between 75 four guide posts 171 and positioned by a plate support

172 formed, for example as illustrated in Fig. 39, and mounted above the surface of the packaging machine for sliding movement between forward and rearward limit positions transversely of the machine. The plate support 172 has a supporting tray 173 extending transversely thereof adjacent the lower surface of the plate support which is positioned beneath the stack of pie plates when the plate support is in its rearward limit position and supports the weight of the entire stack of pie plates.

Secured to the rearward end of the plate support 172 and extending forwardly therefrom in spaced parallel relation with the upper surface of the plate support is a pair of separating knives 174, 174 which are operable to be inserted between the flanges of the lower and next adjacent pie plate in the stack of pie plates to thereby permit the lower pie plate to be dropped away from the rest of the stack. The forward ends of the separating knives are sharpened and terminate adjacent the rearward edges of the supporting tray 173. The vertical distance between the upper surface of the supporting tray and the sharpened edges of the separating knives is slightly greater than the height of one pie plate so that the separating knives will be projected to a position lying immediately above the flange of the lower pie plate of the stack of pie plates when the plate support 172 is actuated to its forward limit position. The separating knives are carried by the plate support 172 at opposite sides of the stack of pie plates and are spaced apart from one another a distance slightly less than the diameter of the flange of the pie plate so that the upper surfaces of the two knives will rest beneath the flange of the pie plate in the stack of pie plates when the knives are actuated to their forward limit position.

The entire plate support 172 is mounted for sliding movement in a pair of grooves 175, 175 provided along the inner side edges of a pair of guide blocks 176, 176 which are positioned above the frame of the packaging machine and secured thereto, for example as indicated at 177, 177 in Fig. 36. The guide blocks 176, 176 direct the movement of the plate support 172 transversely of the packaging machine in the proper position beneath the stack of pie plates.

The lower ends of the posts 171 project downwardly between the knives 174, 174 around the edges of the stack of pie plates to prevent any lateral movement of the pie plates. In addition, a guide plate 178 is provided extending transversely between the knives 174, 174 and secured to the guide post supports 171a, 171a. This guide plate 178 prevents rearward movement of the lower pie plate of the stack of pie plates while the knives are being retracted. By the construction set forth above, when the guide plate 178 is in its rearward limit position the entire stack of pie plates is supported by the supporting tray 173 which extends transversely of the plate support 172. Upon actuation of the plate support 172 to its forward or projected limit position the supporting tray 173 is removed from its position beneath the stack of pie plates simultaneously with the insertion of the pair of separating knives 174, 174 between the lower pie plate of the stack of pie plates and its next adjacent pie plate. This permits the lower pie plate of the stack of pie plates to be dropped downwardly when the plate support 172 reaches its forward limit position. The operation of the conveyor 161 is timed with the operation of the plate support 172 so that the conveyor will stop with a finished box positioned beneath the stack of pie plates before the plate support 172 is actuated to its forward limit position. This permits the bottom pie plate to be dropped into the finished box.

Actuation of the plate support 172 is effected by the shuttle cam 85. As described previously, the shuttle cam 85 causes rocking movement of an arm 87 about its pivot point 88, for example as illustrated in Fig. 9. A tie rod 181 is connected to the arm 87 and extends outwardly therefrom at right angles to the axis of the arm 87.

The opposite end of the rod 181 is secured to a connecting link 182 which in turn is pivotally secured to a yoke 183 carried by the rearward edge of the plate support 172, for example as illustrated in Fig. 32. Thus, during each revolution of the shuttle cam 83 the plate support 172 is actuated first to its forward limit position and then to its rearward limit position. This in turn causes one pie plate to be dropped into a box positioned beneath the stack of pie plates.

In accordance with the present invention means are provided to insure the insertion of a pie plate into a finished box during each actuation of the plate support 172. The pie plates 53 are normally formed of paper mache and the thickness of the edges of the pie plate is not always uniform. Accordingly, in many instances, it is possible for two plates each having thick portions on their edges to be so positioned that the thick portions are in engagement with one another. In this case when the knives are inserted between the two pie plates the portion of the upper pie plate will be distorted by the separating knives 174. This distortion of the edge of the pie plate may, during a subsequent operation of the plate support 172, prevent the knives from properly separating the next two adjacent pie plates. Accordingly, means are provided to cause rotation of the entire stack of pie plates during each operation of the plate support 172 and thereby present a new edge surface to the knives during each insertion of the knives. This is accomplished by means of a pawl 185 having an elongated plate engaging portion 185a thereon which is forced into engagement with the stack of pie plates during each actuation of the plate support and rotates the stack of pie plates a fraction of a revolution. The pawl 185 is pivotally secured to the mid-point of a cam arm 186, for example as indicated at 187 and the cam arm is pivotally mounted to a post 188 extending upwardly from the guide post support 171a which, in turn is secured to the guide block 176, for example as illustrated in Figs. 33 and 35 and retained in a retracted position by means of a coil spring 191. In addition, a second coil spring 192 interconnects the mid-point of the pawl 185 with the cam arm 186 and normally urges the forward edge or plate engaging portion 185a into engagement with the side edges of the stack of pie plates. A pin 193 projecting upwardly from the rear corner of the plate support 172, as illustrated in Fig. 39, is adapted to engage a cam surface 194 on the outer side edge of the cam arm 186 during forward movement of the plate support 172 to thereby pivot the cam arm in the clockwise direction with respect to Fig. 33 thus forcing the pawl 185 into engagement with the side edge surface of the stack of pie plates causing the pie plates to rotate a fraction of a turn. This construction thereby presents a new surface on the edge of the pie plates to the separating knives 174 during each cycle of operating of the plate support 172 and insures proper separation of the pie plates.

After a pie plate is inserted into a finished box. The box is moved by the conveyor 162 to section C of the machine wherein a pie 54 is manually placed in the pie plate 53 in the finished box 52. The box, pie plate and pie are then conveyed by the conveyor to section D of the machine wherein a strip of cellophane 55 is positioned over the open upper end of the box and glued in this position on the box to complete the packaging operation.

Figs. 40 to 50, inclusive (sheets 11 to 15 of the drawings), illustrate the construction and operation of section D of the machine wherein the cellophane strips 55 are secured across the open upper end of the box 52. The mechanism in section D of the machine and the conveyor 162 are driven by the main drive shaft 65 of the machine which extends out from the rear edge of the gear reducer 66. With reference to Fig. 48, the main drive shaft 65 drives a stub shaft 201 by means of a

chain drive passing over a pair of sprockets 202 and 203 secured to the shafts 65 and 201, respectively. By this construction the shaft 201 is continuously rotated in one direction. A shaft 205 extending transversely of the packing machine also is rotated continuously in one direction by means of a pair of bevel gears 206, 206 interconnecting the shaft 205 and the main drive shaft 65. This shaft 205 has a sprocket 207 thereon which drives a part of the feed mechanism at Section D of the machine. In addition, a pair of drive sprockets 208 and 209 are driven intermittently through intermittent drive mechanism designated generally as 211 which is actuated by rotation of the shaft 205. The sprocket 209, in turn, engages the endless chain conveyor 162 and causes intermittent actuation thereof.

With reference to Figs. 48, 49 and 50 the intermittent drive mechanism 211 consists essentially of an eccentric 212 pinned to the shaft 205 and rotatably mounting a rocker arm 213. The arm 213 carries a pair of pivot pins 214 and 215 at the opposite ends thereof which in turn mount tongue members 216 and 217 adapted to be inserted into slots 218 in a drive wheel 219. The one pivot pin 214 at the right hand side of the bushing, with respect to Fig. 49, has a slot 221 in the lower edge thereof which is engaged over a guide strip 222 secured to one wall of the housing for the intermittent drive mechanism 211. This construction permits the rocker 213 to be oscillated about the pivot pin 214 while the pin 214 is sliding longitudinally of the guide strip 222. Rotation of the eccentric 212 in the clockwise direction, with respect to Fig. 49, along with the shaft 205 will first cause the left hand end of the rocker 213 to be moved upwardly pivoting the rocker clockwise about the pivot pin 214. At the same time the right hand end of the rocker is moved to the right with respect to Fig. 49 along the guide strip 222.

When the left hand end of the rocker 213 reaches its highest position due to rotation of the eccentric 212, the tongue 217 carried thereby will have moved to the right relative to the drive wheel 219 and be engaged in one of the slots 218 in the periphery thereof. Further rotation of the eccentric 212 causes the left hand end of the rocker to be moved downwardly thus causing rotation of the drive wheel 219 in the counter-clockwise direction with respect to Fig. 50. When the rocker reaches its lowest limit position due to rotation of the eccentric 212 the finger 217 carried at the left hand end of the rocker is moved to the left with respect to Fig. 50 and is disengaged from the slot 218. A guide arm 220 pivotally mounted on the shaft 205 is slidably engaged by a groove in the pivot pin 215 and maintains the tongue 217 in position for engagement in a drive wheel slot 218. Continued rotation of the eccentric 212 will cause the tongue 217 on the rocker to repeat this cycle of operation and thus translate the continuous rotation of the shaft 205 in the clockwise direction relative to Figs. 49 and 50, into intermittent rotation of the drive wheel 219 in the counter-clockwise direction relative to Figs. 49 and 50. A positive amount of incremental movement of the drive wheel 219 is assured by means of the holding tongue 216 carried by the pivot 214 at the right hand end of the rocker 213. The tongue 216 is so positioned that it is engaged in a slot 218 when the tongue 217 is disengaged from a slot 218 and upon engagement of the finger 217 in a slot 218 the finger 216 is disengaged from a slot in the drive wheel.

As a box 52 (see Fig. 41) is moved longitudinally of the machine by the chain conveyor 162 it is brought into engagement with a first box positioner 225 operable to properly position the box relative to the longitudinal axis of the packaging machine. This box positioner 225 has a flared entrance opening 226 at the inlet end thereof which engages the forward end of the box and transposes the box transversely of the packaging machine to its

proper position. Further longitudinal movement of a box by the conveyor 162 brings the box into engagement with a second box positioner 227 which positions and maintains the box in a predetermined position while glue 5 is being applied along the upper portions of the two opposite end walls of the box.

While the box is held stationary beneath the second box positioner 227, a pair of ball point glue applicators 228, 228 are moved transversely of the packaging machine with the rotatable ball point of the glue applicators in engagement with the upper portions of the end walls 10 of the box beneath the box positioner 227. Glue is fed to the ball points of the applicators from a glue vat 231 through a pair of flexible hoses 232, 232. By this construction there is always a supply of glue at the ball points of the applicators and the glue is readily applied to the desired portions of the box upon actuation of the glue applicators 228, 228. The glue applicators are caused to move transversely of the packaging machine by means of 15 a glue cam 233 formed for example as illustrated in Fig. 43 and secured to the stub shaft 201. A cam follower 234 carried by an arm 235 is in engagement with the peripheral surface of the glue cam 233 and a tension spring 236 connected to the arm 235 maintains the cam follower in engagement with the surface of the cam 233. In addition a yoke portion 237 formed integrally with the inner end of the arm 235 embraces the shaft 205 thus 20 guiding the movement of the arm 235. A glue lever 238 having its lower end pivotally secured to the arm 235, for example as indicated at 241 in Fig. 43, is pivotally secured at its mid point to the frame of the packaging machine, for example as indicated at 242. During rotary movement of the stub shaft 201 and the cam 233 the cam follower 234 is caused to move transversely of the 25 packaging machine and oscillation of the glue lever 238 is effected about its pivot point 242.

With reference to Fig. 44, the upper end of the glue lever 238 is pivotally secured through a connecting link to a cross-head 243 which is mounted for reciprocation 30 transversely of the packaging machine on a guide 244. The cross-head 243 has a pair of downwardly extending arms 245, 245 at opposite sides thereof which carry the ball point glue applicators 228, 228 and maintain the applicators in their set positions relative to the end walls 35 of the box 52 which is positioned beneath the second box positioner 227.

The rotation of the shaft 201 is timed with respect to the intermittent operation of the conveyor 162 so that the conveyor 162 stops with a box beneath the box positioner 227 and then the glue cam is caused to actuate the lever 238 and the glue applicators 228, 228 to thereby apply glue to the opposite end walls of the box. The conveyor 162 is then moved a further step positioning a second box beneath the box positioner 227 and the gluing 40 operation is repeated.

It should be noted that the application of glue is accomplished by a single traverse of the glue applicator.

With reference to Fig. 44, after glue is applied to the ends of the box 52 it is moved longitudinally of the packaging machine to the position shown in the center of 45 Fig. 44 wherein the box is ready to receive a strip of cellophane 55. The cellophane is in continuous roll form 247 and is carried on a roll 247a supported in bearings in a bracket 248 extending upwardly from the packaging machine. Pivotally supported in the bracket 248 above the roll 247 by trunions 249a, 249a is a conventional cellophane printer 249, for example of a type similar to model No. 40 manufactured by the American Marking Corp. The printer 249 has a rotatable printing drum 249b at one end thereof which prints any desired matter on the surface of the cellophane web as it is drawn from the roll 247. The cellophane then passes over a first idler roll 250 and then a tensioning roll 251 50 carried by a pair of pivotally mounted arms 252, 252

one of which has one end of a brake strap 253 secured thereto.

The opposite end of the strap passes over and around on extended end portions of the cellophane supporting roll and is fixedly secured to the bracket 248. Thus the roll 251 and associated arms 252 are yieldably supported with respect to the cellophane web and the weight of such suspended units utilized to exert a drag on the cellophane roll placing the cellophane web under tension. In addition, pressure applying means indicated at 252a may be used in an obvious manner to vary the degree of tension.

The opposite end of the cellophane supporting roll 247a is provided with an annular recess 247b which is adapted to receive a disc-like member secured to one end of a laterally adjustable hand screw carried in the bracket 248. Such means indicated generally at 247c, provides adjustment of the cellophane supporting roll transversely of the machine to insure proper longitudinal alignment of the cellophane web.

In accordance with the present invention means are provided to feed the cellophane intermittently, cut off a strip of cellophane of predetermined length, and apply the cellophane to the finished box across the open upper end thereof. To accomplish this, upper and lower feed rolls 254 and 255, respectively, are driven intermittently from the intermittent rotating sprocket 208 (see Fig. 48) through a chain 256, sprockets 256a and 256b which drives a sprocket 257 secured to a shaft 258 mounting the lower feed roll 255, for example as illustrated in Fig. 43. A pair of gears 259, 259 interconnect the upper and lower feed rolls 254 and 255 to effect simultaneous rotation thereof.

While the lower feed roll 255 is mounted in bearings fixedly secured in the bracket 248, the uppermost roll 254 is journaled in bearing blocks 254a, 254a yieldably supported in guideways formed therein. Compression springs 263, 263 backing up the bearing blocks normally maintain the roll 254 in pressure contact relationship with the roll 255 to effect feeding of the cellophane web. However, should it be desired to interrupt the feed thereof at any time while the machine is in motion, manual means is provided in the form of a readily accessible hand lever shown at 161. Having a pair of spaced parallel legs pivotably supported on the bracket 148 at 262, 262, the free ends thereof extend beyond the pivots and lie beneath pin projections on the bearing blocks 254a, 254a. Pressure applied by way of the handle portion effects the separation of the rolls 254, 255 in obvious manner and discontinues the feeding thereof. Such operation thereof is also desirable in initially introducing the cellophane web during set-up.

As the cellophane leaves the feed rolls 254 and 255 it passes downwardly over a feed and cutting table 264. With reference to Figs. 44 and 47 upper and lower guide wires 265 and 266 extend rearwardly from vertically spaced supporting blocks 267 and 268, respectively. Substantially with the surface of the feed table 264 they span the intervening space between the end of said table and the feed rolls and pass partially around grooves provided in the peripheral surfaces of the feed rolls 254 and 255. The confronting faces of the several sets of guide wires are relatively off-set vertically to opposite sides of a common plane (see Fig. 47) so as to effect a rippling longitudinally of the cellophane web as it passes therebetween thereby imparting rigidity to the web in order that it be projected accurately across the surface of the feed table during high speed operation of the machine. The feed rolls 254 and 255 stop operation when the leading edges of the strip of cellophane has reached the position illustrated in Fig. 44 and is overlying the leading end of the box positioned beneath the cellophane applying station.

After the feed rolls have advanced the cellophane on the feed table 264 to the position indicated, a disc-type

knife 271 formed, for example as illustrated in Fig. 44, and having a cutting edge thereon which cooperates with a stationary cutting edge 272 carried by the feed table 264 is actuated to cut the sheet of cellophane into the

desired length for later application over the open upper end of the finished box. The knife 271 is moved transversely of the feed table 264 when it is desired to cut the cellophane. Actuation of the knife is caused by the glue cam 233 which also operates the ball point glue applicators 228, 228. This is accomplished by means of a connecting rod 273 pivotally secured to the glue lever 238, for example as illustrated at 274 in Fig. 43. The upper end of the rod 273 is secured to a knife bracket 275 which in turn is slidably mounted on a square shaft 276 extending transversely of the packaging machine. The knife 271 is in the form of a roller of frusto-conical section having a concave face (see Fig. 44) and is resiliently secured to the forward edge of the knife bracket 275, for example by means of an adjusting bolt 277 and a spring 278 which forces the knife blade forwardly into engagement against the cutting edge 272 provided in the surface of the feed table 264. From the foregoing it will be obvious the knife is self-sharpening.

The knife may be lifted out of action manually by means of a handle provided at 276a which attaches to one end of the shaft 276, said shaft being supported for rotative movement in a pair of fixed bearings on the feed table 264.

While the knife 271 and the glue applicator 228 are being actuated, a pair of continuously rotating brush rolls 281, 281 are lowered and then elevated to force the leading edge of the strip of cellophane on the feed table downwardly along the end of a box positioned beneath the feed table and into engagement with a strip of glue on the end of the box to thereby secure the cellophane to the box. The pair of brushes 281, 281 are driven from the continuously rotating sprocket 207 as shown in Fig. 48 which in turn drives a sprocket 282

40 by means of a conventional chain. A second chain drive passing over a sprocket 283 rotatable with the sprocket 282 drives a pair of sprockets 284, 284 secured to shafts 285, 285 mounting the brush rolls 281, 281. While these brush rolls 281, 281 are rotating, a brush

45 cam 286 mounted on the stub shaft 201 which also carried the glue cam 233 operates to lower the brushes 281, 281 and cause the leading edge of the cellophane to be secured to the leading edge of the box. The brush cam 286 is engaged by a cam follower 287 which lowers

50 a brush bracket 288. A pair of guide arms 289, 289, as shown in Fig. 43, extend downwardly from the brush bracket 288 and compression springs 291, 291 positioned about the arms 289, 289 urge the brush bracket 288

55 downwardly thereby actuating the brushes to their lower limit position when the cam follower 287 engages the low portions on the cam 286. By this construction it is apparent that the brushes 281, 281 rotate continuously and are intermittently lowered into position to wipe the leading edge of the cellophane into engagement with

60 the leading end of a box. The conveyor 162 then operates to position the box at the next station of the packaging machine wherein the brushes 281, 281 wipe the trailing edge of the sheet of cellophane 55 into engagement with the strip of glue applied to the opposite end of the box. At the same time the brushes 281, 281

65 wipe the feeding edge of the next sheet of cellophane into engagement with the leading end of the next adjacent box.

Since the boxes being transported by the conveyor are 70 pushed forwardly by the conveyor pins 163, means must be provided to position the box and maintain the box in the desired position when the brush roll is brought downwardly to wipe the trailing edge of the sheet of cellophane 55 against the trailing end of the box. This is accomplished in the present invention by means of

a positioning plate 292 which is movable between upper and lower limit positions by the brush bracket 288. The positioning plate 292 is pivotally secured, for example as indicated at 293 in Fig. 46, at a point to the left of its center of gravity to the lower end of a pair of arms 294, 294.

For this reason the plate when thus suspended freely will always tend to tilt clockwise about its pivot. The arms 294 are fixedly secured to a shaft 295 rotatably mounted in bearing supporting members 296, 296 extending upwardly from the bracket 288. A torsion spring 295a adjustably secured to one end of the shaft 295 serves to bias the shaft rotatively in a counter-clockwise direction and to further supplement the pressure of the freely hung positioning plate. Means is provided at 295b to limit the extent of such movement. Proper adjustment of the device is obtained when the adjusting means 295b is provided with a clearance with respect to the member 296 and the full weight of the plate 292 is effective on the top of the box 52 as shown in Fig. 44. When, however, the respective box is advanced by the conveyor 162 and thus removes its support of the plate 292, means 295b functions to permit lowering of the pivot 293 to a point somewhat lower than normal box height while the plate tends to rotate in a clockwise direction due to gravity. This has the effect of concentrating the pressure of the plate against the leading edge of the incoming box on initial contact therewith, and then as the box continues to advance, returns the pivot 293 and plate to the positions shown in Fig. 44. In this position downward movement of the brush carrying bracket 288 is initiated with the resultant lowering of the plate supporting shaft 295. This relative shortening of the lever arms 294 causes the plate 292 to move along the box to the left thereby urging the box rearwardly into firm engagement with the conveyor pins 163 at the same time drawing the associated cellophane sheet 55 taut as the brush roll wipes down the trailing edge thereof. A blade 297 of Teflon or other glue resistant material having a bevelled edge and also secured to the bracket 288 applies holding pressure against the leading edge of the box during downward movement of the bracket and subsequent brushing operation preventing this glued edge of the cellophane from being loosened.

A modified form of ram assembly and die for folding the box blank and inserting the locking flaps into the locking slits on the walls of the box blank which is of relatively simple construction and is highly effective in operation and use is illustrated in Figs. 51 to 58 inclusive, of the drawing. In this embodiment of the present invention, a ram assembly 300 is provided which has a cross sectional configuration generally similar to that of the previously described ram assembly 72 and is secured to the lower end of the shaft 73. This ram assembly 300 is actuated between upper and lower limit positions by means of the ram cam 78 and during movement toward its lower limit position the ram assembly engages a box blank 51 positioned by the box blank shuttle 82 over a die 301 and inserts the box blank into the die thereby folding the side and end walls of the box blank upwardly as previously described.

An important feature of this form of the present invention is the provision of means to open the slit openings 62 in the side walls of the box after the box has been inserted into the die opening so that the locking tabs may be readily inserted into the slit openings. To this end a pair of slit openers 302, 302 formed, for example, illustrated in Fig. 53 of the drawings are pivotally mounted as indicated at 303, 303 to opposite sides of the ram assembly 300. Each slit opener comprises a cross arm 304 having a pair of downwardly extending pusher feet 305, 305 at opposite ends thereof which are adapted to engage the inner surface of the side walls of the box immediately below the slits 62 and displace the lower portion of the side walls of the box outwardly relative to the

upper portion of the side walls. An arm 306 extends upwardly from the cross arm 304 and carries a cam finger 307 which cooperates with the side walls of the die opening to pivot the slit opener 302 about its pivot point 303 and force the pusher feet 305, 305 into engagement with the side walls of the box to open the slits in the box. A pair of coil springs 308 interconnect the pusher feet of opposite slit openers beneath the pivot points 303, 303 to normally maintain the pusher feet inwardly of the side walls of the ram assembly. As the ram assembly 300 reaches its lower limit position the cam fingers 307, 307 of the slit openers 302, 302 engage the inner surface of the side walls of the die 301, for example as illustrated in broken lines in Fig. 51, and pivot the slit openers about their pivot points so that the pusher feet of the slit openers are projected outwardly beyond the side edges of the ram assembly 300.

When the ram assembly 300 reaches its lower limit position in the die 301 with the side and end walls of the blank folded upwardly and the triangular flaps 59 of the box blank folded inwardly in alignment with the side walls, the pedestals 118, 118 engage the lower surface of the box blank and the pedestal hooks 131, 131 are engaged over the upper end of the side walls in the box blank to maintain the box blank in position on the pedestals 118, 118. In this position of the ram assembly 300 and pedestals, the slit openers 302, 302 are in the position illustrated in Fig. 55 with the pusher feet 305 causing the portion of the side walls beneath the slits to be deflected outwardly beyond the plane of the side walls. The ram cam and pedestal cam then cause the ram assembly 300 and pedestals 118, 118 to move upwardly together until the pedestals 118, 118 reach their upper limit position, whereupon movement of the pedestals 118, 118 is stopped while the ram assembly continues moving upwardly out of the die opening. During upward movement of the pedestals 118, 118 from the position where they first engage the lower surface of the box blank to their upper limit position, the outwardly displaced side wall portions of the box blank are engaged over the outer surfaces of fingers 309 extending downwardly below the side walls of the die adjacent the inner surface of the die. These fingers 309 maintain the lower portions of the side walls in their outwardly displaced position, for example as illustrated in Fig. 57, while the pusher feet are caused to withdraw inwardly of the ram assembly 300 by the springs 308 during movement of the ram assembly 300 toward its upper limit position.

After the pedestals 118, 118 reach their upper limit position and the ram has been retracted a pair of folding plates 311, 311 mounted on the shaft 148, 148 which extend outwardly beyond the side walls of the die are pivoted inwardly into engagement with the triangular flap portions of the box blank to fold the triangular flap portions downwardly and insert the locking tabs into the opened locking slits 62. The folding plates 311, 311 are mounted for movement between retracted and projected limit positions on the shafts 148, 148 and are actuated by the knife cam 156 in the manner previously described for the operation of the knife assemblies 147, 147. Pivotally secured to the outer walls of the folding plates 311, 311 are latch members 312 which are spring biased to the position illustrated in Fig. 52 and are adapted to engage the upper surface of the triangular flap portions to maintain the same in position against the inner surface of the folding plates 311, 311. The upper limit position of the pedestals 118, 118 is adjusted so that the fold line of the triangular flap portions lies on the axis of the shafts 148, 148. By this construction the triangular flaps are always folded downwardly along their fold lines.

During movement of the folding plates 311, 311 to their projected limit position the locking tabs 61 of the box blank are forced downwardly into the slit openings 62 in the side walls of the box blank. The lower portion of the side walls beneath the slit openings are held

in an outward displaced position by means of the fingers 309 which in turn causes the upper portions of the side walls above the slit openings to buckle inwardly permitting the locking tabs to be inserted between the side walls of the die and the outer edges of the side walls of the box blank, for example, as illustrated in Figs. 55 and 58. After the folding plates 311, 311 have reached their projected limit position, the pedestals 118, 118 are moved downwardly toward their lower limit position thus removing the completed box from the die opening and the folding plates 311, 311 are moved to their retracted limit position. The machine is now ready to fold another box blank into a finished box upon the next actuation of the ram assembly 300.

From the foregoing it is apparent that the present invention provides a novel packaging machine which forms a box blank into a finished box, inserts an article into the box, then secures a sheet of cellophane over the box to seal the same and accomplishes these operations quickly and automatically.

While particular embodiments of the present invention have been illustrated and described herein it is not intended to limit the invention to such a disclosure and changes and modifications may be incorporated and embodied therein within the scope of the following claims:

We claim:

1. In a packaging machine operable to form a box blank into a finished box; said box blank comprising a rectangular base portion and side and end wall portions foldably secured to said base portion, support means operable to support a supply of box blanks, a ram assembly mounted adjacent said support means for movement between opposite limit positions, drive means operable to actuate said ram assembly between said opposite limit positions, means defining a die opening positioned in axial alignment with said ram assembly into which said ram assembly projects during movement toward one of said limit positions, a box blank shuttle operable to transfer a box blank from said support means to a position overlying said die opening with the rectangular base portion of the box blank coextensive with the die opening, and a plurality of forming edges on said box blank shuttle and adjacent said die opening operable during movement of said ram assembly to said one limit position to engage the side and end walls of the box blank and fold the same upwardly relative to the box blank base portion.

2. In a packaging machine operable to form a box blank into a finished box; said box blank comprising a rectangular base portion, side and end wall portions foldably secured to said base portion, flap portions secured to the upper ends of opposite wall portions, and locking tabs on the side edges of said flap portions operable to be inserted into slits in adjacent wall portions, support means operable to support a supply of box blanks, a ram assembly mounted adjacent said support means for vertical movement between opposite limit positions, drive means operable to actuate said ram assembly between said opposite limit positions, means defining a die opening positioned in axial alignment with said ram assembly into which said ram assembly projects during movement toward one of said limit positions, a box blank shuttle operable to transfer a box blank from said support means to a position overlying said die opening with the rectangular base portion of the box blank coextensive with the die opening, a plurality of forming edges on said box blank shuttle and adjacent said die opening operable during movement of the ram assembly toward said one limit position to engage the side and end walls of the box blank and fold the same upwardly relative to the box blank base portion, and means in said die opening operable after the box blank has been inserted into said die opening by said ram assembly to fold said flap portions downwardly across the upper end of said box and

insert said locking tabs into said slits in the box blank wall portions.

3. In a packaging machine operable to form a box blank into a finished box; said box blank comprising a rectangular base portion, side and end wall portions foldably secured to said base portion, flap portions secured to the upper ends of opposite wall portions, and locking tabs on the side edges of said flap portions operable to be inserted into slits in adjacent wall portions, support means operable to support a supply of box blanks, a ram assembly mounted adjacent said support means for vertical movement between opposite limit positions, drive means operable to actuate said ram assembly between said opposite limit positions, means defining a die opening positioned in axial alignment with said ram assembly into which said ram assembly projects during movement toward one of said limit positions, a box blank shuttle operable to transfer a box blank from said support means to a position overlying said die opening with the rectangular base portion of the box blank coextensive with the die opening, a plurality of forming edges on said box blank shuttle and adjacent said die opening operable during movement of the ram assembly toward said one limit position to engage the side and end walls of the box blank and fold the same upwardly relative to the box blank base portion, a plate pivotally mounted adjacent opposite sides of said die opening operable to engage the flap portions of said box blank after the box blank is in position in said die opening, side lip portions extending forwardly from the edges of said plate in engagement with the box blank locking tabs, means carried by said plate in engagement with said box blank locking tabs operable to guide said box blank locking tabs into said slits in the box blank wall portions, and means operable to cause rotation of said plate to thereby fold said box blank flap portions across the upper end of said box blank and insert said locking tabs into said slits after the box blank has been inserted into said die opening.
4. In a packaging machine operable to form a box blank into a finished box; said box blank comprising a rectangular base and side and end walls foldably secured to said base, support means operable to support a supply of box blanks, a ram assembly mounted adjacent said support means for vertical movement between upper and lower limit positions, drive means operable to actuate said ram assembly between said opposite limit positions, means defining a die opening positioned beneath said ram assembly in axial alignment therewith into which said ram assembly projects during movement toward its downward limit position a box blank shuttle operable to transfer a box blank from said support means to a position overlying said die opening with the rectangular base portion of the box blank coextensive with the die opening, a plurality of forming edges on said box blank shuttle and adjacent said die opening operable during movement of the ram assembly toward its lower limit position to engage the side and end walls of the box blank and fold the same upwardly, a pedestal mounted beneath said die opening for vertical movement between upper and lower limit positions, drive means for said pedestal operable to actuate the same between said upper and lower limit positions and insert the pedestal into the die opening during movement thereof toward said upper limit position, and latch means carried by said pedestal operable to engage the box and transfer the same from the ram assembly to the pedestal to remove the box from the die opening during movement of said pedestal to its lower limit position.
5. In a packaging machine operable to form a box blank into a finished box; said box blank comprising a rectangular base, side and end walls foldably secured to said base, flap portions secured to the upper end of opposite wall portions and locking tabs on the side edges of said flap portions operable to be inserted into slits

21

in adjacent wall portions, support means operable to support a supply of box blanks, a ram assembly mounted adjacent said support means for vertical movement between upper and lower limit positions, drive means operable to actuate said ram assembly between said opposite limit positions, means defining a die opening positioned beneath said ram assembly in axial alignment therewith into which said ram assembly projects during movement toward its downward limit position, a box blank shuttle mounted for sliding movement between said support means and said ram assembly operable to transfer a box blank from said support means to a position overlying said die opening with the rectangular base portion of the box blank coextensive with the die opening, a plurality of forming edges on said box blank shuttle and adjacent said die opening operable during movement of the ram assembly toward its lower limit position to engage the side and end walls of the box blank and fold the same upwardly, a pedestal mounted beneath said die opening for vertical movement between upper and lower limit positions, drive means for said pedestal operable to actuate the same between said upper and lower limit positions and insert the pedestal into the die opening during movement thereof toward said upper limit position, latch means carried by said pedestal operable to engage the box blank and transfer the same from the ram assembly to the pedestal, a plate pivotally mounted adjacent opposite sides of said die opening operable to engage the flap portions of said box blank secured to said pedestal when the pedestal is in its upper limit position, side lip portions extending forwardly from the edges of said plates in engagement with the box blank locking tabs, arcuate knives carried by said plates in engagement with said box blank locking tabs and having forward edge portions extending in advance of said locking tabs, the distance between the forward edge portions of said knives being slightly less than the distance between said opposite wall portions of said box blank, kicker members operable to engage said wall portions of said box blank above said locking slits and force said wall portions inwardly, means operable after actuation of said kicker member to cause rotation of said plates and force said knives and said locking tabs downwardly into the box blank locking slits, means to retract said plates and said knives, and means simultaneously actuatable upon retraction of said knives to lower said pedestals and remove the finished box from said die opening.

6. In a packaging machine operable to form a box blank into a finished box; said box blank comprising a central rectangular base member and side and end wall portions foldably connected to said base member, support means operable to support a supply of box blanks, box forming mechanism operable to form said box blank into a finished box, a box blank shuttle mounted beneath said support means for sliding movement between forward and rearward limit positions and actuatable during movement toward said forward limit position to transfer a box blank from said support means to said box forming mechanism, means slidably mounting said box blank shuttle for movement between said forward and rearward limit positions, drive means operable to actuate said box blank shuttle between said forward and rearward limit positions, and forming edges on said box blank shuttle co-operable with said box forming mechanism in the forward limit position of said box blank shuttle to fold said side and end wall portions of said box blank upwardly during actuation of said box forming mechanism.

7. In a packaging machine operable to form a box blank into a finished box; said box blank comprising a central rectangular base member and side and end wall portions foldably connected to said base member, support means operable to support a supply of box blanks, box forming mechanism operable to form said box blank into a finished box, a box blank shuttle mounted beneath said support means for slidable movement between for-

22

ward and rearward limit positions, a plate secured to said shuttle and positioned beneath the box blanks carried by the support means when the shuttle is in said forward limit position, arm portions projecting forwardly from said plate and positioned beneath said support means when said box blank shuttle is in its rearward limit position, an upwardly extending lip portion adjacent the forward end of said plate in engagement with a box blank carried by said forwardly extending arm portions in the rearward limit position of said shuttle, said lip portion operable to force a single box blank forwardly during movement of said box blank shuttle to its forward limit position and transfer said box blank to said box forming mechanism, means slidably mounting said box blank shuttle for movement between said forward and rearward limit positions, drive means operable to actuate said box blank shuttle between said forward and rearward limit positions, and forming edges on said box shuttle to fold said side and end wall portions of said box blank upwardly during actuation of said box forming mechanism.

8. In box forming mechanism for forming a box blank into a box, said box blank comprising a rectangular base portion and side and end wall portions foldably connected to said base portion, means defining a die opening to receive the box blank, means to insert the box blank into the die opening with the side and end walls thereof folded upwardly to a position at right angles with the base portion of the box blank, a pedestal mounted for vertical movement between upper and lower limit positions and operable to be inserted into the die opening in engagement with the box blank therein in said upper limit position, and latch means carried by said pedestal operable to engage the upper ends of said box blank wall portions when the pedestal is in said upper limit position to maintain said box blank in said die opening.

9. In box forming mechanism for forming a box blank into a box, said box blank comprising a rectangular base portion and side and end wall portions foldably connected to said base portion, means defining a die opening to receive the box blank, means to insert the box blank into the die opening with the side and end walls thereof folded upwardly relative to the base portion of the box blank, a pedestal mounted for movement between predetermined limit positions and operable in one limit position thereof to be inserted into the die opening in engagement with the box blank therein in said upper limit position, latch means carried by said pedestal operable to engage the upper ends of said box blank wall portions when the pedestal is in said one limit position to maintain said box blank in said die opening, pedestal actuating mechanism operable to actuate the pedestals between said limit positions, and latch release mechanism actuatable during movement of said pedestals to the other limit position thereof to disengage said latch means from said wall portions.

10. In box forming mechanism for forming a box blank into a box, said box blank comprising a rectangular base portion and side and end wall portions foldably connected to said base portion, means defining a die opening to receive the box blank, means to insert the box blank into the die opening with the side and end walls thereof folded upwardly to a position at right angles with the base portion of the box blank, a pedestal mounted for vertical movement between upper and lower limit positions and operable to be inserted into the die opening in engagement with the box blank therein in said upper limit position, latch means carried by said pedestal operable to engage the upper ends of said box blank wall portions when the pedestal is in its upper limit position to maintain the box blank in said die opening, pedestal actuating mechanism operable to actuate the pedestal between said upper and lower limit positions, latch release mechanism actuatable during downward move-

ment of said pedestal to disengage said latch means from said box wall portions, and conveyor means operable when said pedestal reaches said lower limit position to remove the box therefrom.

UNITED STATES PATENT OFFICE
CERTIFICATE OF CORRECTION

Patent No. 2,860,549

November 18, 1958

Joseph P. Mancuso et al.

It is hereby certified that error appears in the printed specification of the above numbered patent requiring correction and that the said Letters Patent should read as corrected below.

Column 20, line 51, after "position" insert a comma; column 21, line 72, for "suply" read -- supply ---; column 22, line 18, after "box" insert -- blank --; line 19, after "shuttle" insert -- cooperable with said box forming mechanism in the forward limit position of said box blank shuttle ---.

Signed and sealed this 3rd day of March 1959.
